ROLLING SHELF

Floyd J. Powell, Marshall, Mo., assignor to Ullin
A. Burnett, Marshall, Mo.

Application May 9, 1932. Serial No. 610,291

8 Claims. (Cl. 214—65)

This invention relates to rolling shelves, and more particularly to a shelf or rack having a movable platform for supporting articles thereon, the principal object of the invention being to provide and adapt such a device for use on trucks and other vehicles for the transportation and delivery of various articles and commodities, but without limitation to said particular application and use. Among other objects to be attained is to produce a structure which is simple and 10 easily operated, yet durable and possessing the requisite load sustaining qualities and at the same time being inherently yieldable to a limited extent in order to compensate for the ordinary torsions and strains to which the body of a 15 vehicle is subjected in use. Further objects and advantages of the invention will hereinafter more fully appear.

The invention consists in the novel general structural arrangement and adaptation, and in 20 the several parts and combinations and arrangements of parts as hereinafter described and pointed out with particularity in the appended claims.

In the accompanying drawings, forming part 25 of this specification, and illustrating a practical adaptation of the invention,—

Fig. 1 is a top plan view of the rack or shelf frame with the movable platform and operating parts assembled thereon, the movable platform 30 being adjusted with its article pusher element in rearmost position;

Fig. 2 is a similar view, with the movable platform operated and the article pusher element in forward position, and parts of the structure being broken away to disclose details of 35 other parts otherwise hidden from view;

Fig. 3 is a longitudinal section, taken substantially on the line 3—3 of Fig. 1;

Fig. 4 is a longitudinal section, taken substantially on the line 4—4 of Fig. 2;

Fig. 5 is a view, on an enlarged scale, and illustrated as a cross-section, taken substantially on the line 5—5 of Figs. 1 and 3;

Fig. 6 is a cross-section, on an enlarged scale, 45 taken substantially on the line 6—6 of Figs. 1 and 3, but showing the modification of the structure of the article pusher element of the movable platform and also of certain parts of the rack or shelf frame;

Fig. 7 is a fragmentary view, in longitudinal section, taken substantially on the line 7—7 of Fig. 6;

Fig. 8 is a fragmentary partial plan view and horizontal section, on an enlarged scale, of the 50 opposite end portions of the rack or shelf frame

and adjacent cooperating portions of the mechanism for supporting and adjusting the movable platform;

Fig. 9 is a fragmentary view, on an enlarged scale, and in vertical section, taken substantially on the line 9—9 of Fig. 8; and

Fig. 10 is a detail sectional view illustrating the preferred practical means for attaching the transverse article supporting slats and article pusher element of the movable platform to the 60 endless belt members.

Referring now to the drawings, the numeral 15 designates a pair of longitudinal side frame members which, as shown, are in cross-sectional form of ordinary commercial channel beams with their flange portions 16 disposed inwardly. These side frame members 15 are connected at intervals intermediate their ends by cross frame members 17 which are integrally welded or otherwise secured at their ends to said side frame members. Said cross frame members 17 may be of any desirable cross-section, but, as shown, they are in the form of plain flat bars. The end portions of the two side frame members 15 are connected by cross members 18 which, as shown, are preferably in 65 the form of channels with their flange portions 19 disposed inwardly of the frame.

In the structure shown the rack or shelf frame comprising the parts just above noted further includes upstanding side frames or plates, there 70 being two practical arrangements illustrated. In the one preferred structure as illustrated in Figs. 1 to 5, inclusive, of the drawings, the upstanding side frames comprise vertical supports 20 which 75 are welded or otherwise secured to the outer faces of the lower side frame members 15, and secured on the inner sides of said vertical supports 20 are longitudinal rails 21. In this connection, it

may be here stated that the several parts described, up to and including the supports 20, 80 are preferably constructed of metal, while said rails 21 are preferably wooden, although they

may be obviously made of metal or any other suitable material such as compressed fiber or the like. A modification of the upper side frame 85 portions of the structure is illustrated in Figs. 6 and 7 of the drawings, wherein vertical supports 90 20^a, similar to the hereinbefore mentioned supports 20, are provided, but, in lieu of the horizontal rail members 21, plates 21^a are substituted,

and said plates, as shown, being of a thickness 95 obviously less than the thickness of the respective rail members 21, inasmuch as the plates are

of a width dimension substantially equal to the overall length of the portion of the respective vertical supports 20^a above the lower side frame 100 105 110

members 15, it, of course, being understood that said members 21 and 21^a are fastened securely by rivets, bolts, or other approved means to said vertical supports 20 and 20^a, respectively.

5 Secured on top of the lower side frame members 15 and to said vertical supporting members 20 or 20^a, as the case may be, are longitudinal angle members 22, said members serving as guideways for the movable shelf or platform and co-
10 operating article pusher element, to be now described. Generally stated, the movable shelf or platform is constructed so as to be flexible and foldable to travel in a manner corresponding to a strap or belt, yet being capable of sustaining
15 the weight of a load thereon when supported on said guideways 22 and other supports and guide members which may be provided supplementary to said members 22, as will be presently described.

As shown, said movable shelf or platform comprises a plurality of transverse bars or slats 23 arranged in spaced parallel relation to each other, the opposite end portions of said members 23 riding normally on the inwardly disposed horizontal flange portions of said members 22, and after
25 leaving said supporting and guiding members 22, in the operation of the device, riding on the lower horizontal inwardly disposed flange portions 16 of said lower side frame members 15, said transverse bars or slats 23 being secured to endless belts or operating elements 24.

In the illustrative structure disclosed in the drawings, the elements 24 are endless belts of the ordinary commercial canvas belting or webbing, leather, or other suitable material, and, as shown
35 more clearly in Fig. 10 of the drawings, the transverse bars or slats 23 of the movable platform, and the bottom members of the article pusher element, to be presently described, are fastened to said belts 24, preferably by means of rivets 25 of the two-piece type, or, in other words, fasteners of the character comprising a headed stud member 26 which is axially bored and screw-threaded to receive a headed screw member 27, by which provision said shelf or platform parts
45 may be readily detached from the belts 24 and replaced, at will.

The endless belts 24 may be provided in any necessary or desirable number, but, obviously, for maintaining the proper correlation of the transverse bars or slats 23 in the operation of the movable platform, at least two of the belts are required, it being understood that additional belts may be desirable, depending upon the dimensions of the shelf, and particularly the transverse dimension thereof. As shown, the belts 24 are supported on rollers 28 and 29, located in the body frame of the shelf or rack respectively adjacent the forward and rear end portions of the frame, said rollers being relatively adjustable in opposed relation to each other and under spring tension tending to move one of the rollers away from the opposite roller at all times, whereby to maintain the belts in a tautened condition.

65 Preferably, the rear roller 29 is the adjustable one. As shown, each of the rollers 28 and 29 comprises a cylindrical open-ended tube 30, on the inside of which, near each end, is provided a fixed collar 31 to afford an annular shoulder against which an inserted antifriction bearing 32 abuts. In this connection, it may be here noted that the shoulder may be provided by means other than said collar 31, that is, by annularly crimping the tube 30 or otherwise forming the shoulder integrally therein, and the antifriction bearing
70 75 may be of any desirable type. As shown, however,

more clearly in Fig. 9 of the drawings, said antifriction bearing comprises an annular outer member 33 having inturned marginal flanges for the retention therein of an outer bearing ring 34 and an inner bearing ring 35 between which a series of balls 36 are interposed, it being understood that the outer body ring 33 is fitted tightly within the roller tube 30, and the outer bearing ring 34 within said outer body ring 33 is freely rotatable with respect to the inner bearing ring 35.

Extending axially through the roller tube 30 is a spindle rod or shaft 37 whose opposite end portions are projected through and beyond the inner bearing rings 35, one end portion of said spindle rod or shaft 37 being screw-threaded, the opposite unthreaded end portion being inserted with a loose fit, as at 38, in a bore provided therefor in the stem portion of a T member 39, the head portion of said T member having a plain longitudinal bore through which an adjusting screw 40 extends with a loose longitudinally slidable fit. The screw 40 is threaded throughout nearly its entire length, and on said threaded portion an adjusting and abutment nut 41 works, and cooperating with said nut 41 is a lock nut 42 by which said nut 41 is fastened in its adjusted position. The screw-threaded opposite end portion 43 of the spindle rod or shaft 37 is inserted in a counterpart threaded bore in the lateral stem portion 44 of a T member 45, which is similar to said T member 39, there being this difference, however, in the end of the spindle rod or shaft 37 is a rounded recess, said recessed portion abutting a screw 46 which is similar to the hereinbefore mentioned screw 40. Said screw 46 extends loosely through a longitudinal bore in the head portion of said T member 45, and it is provided with an adjusting and abutment nut 47, with which cooperates a lock nut 48 in a manner similar to the hereinbefore mentioned nuts 41, 42.

In assembling the parts just above described, the T members 39 and 45 are screwed onto the ends of the spindle rod or shaft 37 until the axes of the bores in the head portions of said T members coincide with the planes of the axes of said screw members 40 and 46 when said screw members are placed in position. When this is accomplished the curved recessed end portion of the spindle rod or shaft 37 is in close proximity to the periphery of the screw 46, but without binding contact therewith, in which relation the T member 45 is free to move longitudinally of the screw 46, but said spindle rod or shaft 37 is held from rotation.

By the construction and relative arrangement of the parts of the roller 29 and its cooperative connections with the screw members 40 and 46, the roller is readily adjusted longitudinally on said screw members to tighten or loosen the endless belts 24, as the case may be, and according to the direction of movement in effecting the adjustment. So, too, while the construction and arrangement is effective for maintaining the endless belts 24 in proper working condition, there is a certain amount of looseness in the engagement of certain parts of the structure which provides for limited yieldability to compensate for ordinary torsions and strains which are placed upon the frame, whereas without such provision there might be a tendency for the spindle rod or shaft 37 to bend or buckle or some other part to be warped or distorted to the extent of interfering with the free rotation of the roller 29.

As shown, the front roller 28 comprises a cylindrical open-ended tube 49, identical with the tube 30 constituting the rear roller 29. Within the tube 49 are the annular abutment rings or shoulder members 50 and antifriction bearings 51, identical with the corresponding parts 31 and 32 in the rear roller tube 30. The front roller 28 is mounted on a spindle rod or shaft 52, similar to the rod or shaft 37 of said roller 29, one end portion 53 of said rod or shaft 52 being screw-threaded and fitted tightly into a correspondingly threaded bore in an elbow member 54, the opposite end portion 55 of said rod or shaft 52 being preferably without screw threads and inserted with a somewhat loose fit into a bore in an elbow member 56. By this arrangement the spindle rod or shaft 52 is normally held from rotation within the one elbow member 54, under normal conditions and operation of the movable article supporting platform or carrier of the shelf, but there is permitted limited relative movement between the shaft and the opposite elbow member 56 to compensate for the effect of limited strains and torsions on the general frame structure.

Each of the elbow members 54 and 56 has the screw-threaded end portion 57 of a tension bar or rod 58 secured tightly therein. The two rods 58 are arranged in parallel relation to each other, and respectively located adjacent to the lower side frame members 15, said rods being mounted in apertures provided therefor in the pair of adjacent cross frame members 17 so as to be freely slidable longitudinally.

Working on the screw-threaded portions of the rods 58 are tension adjusting and abutment nuts 59 which are held in their respective adjusted positions by lock nuts 60. Coiled about the rods 58 and interposed between said adjusting and abutment nuts 59 and one of the cross frame members 17, are springs 61 which are constantly exerting a force tending to move the rods 58 forwardly and thereby create a tension on the endless belts 24, said springs, obviously automatically tautening the belts should they stretch, or said springs will automatically yield to permit shrinkage of the belts, as either of said effects occurs due to weather conditions or usage of the device.

In order to reinforce the body frame of the structure and to afford a support for the transverse bars or slats 23 of the movable article supporting platform, longitudinal bars or rails 62 are mounted on the cross frame members 17, said bars or rails 62, as shown, comprising flat strips whose end portions 63 are turned downwardly and secured, as at 64, to the outer faces of the endmost cross frame members 17, there being a suitable number of these supplemental longitudinal supporting bars or rails according to the width of the movable article supporting platform and the corresponding length of the bar or slat 23.

At the rear of the movable article carrier or platform is an article pusher element comprising an upright abutment frame or plate 65 which engages the rearmost article or articles on the carrier or platform and insures the movement of the articles as the carrier or platform is moved forwardly. As shown in Figs. 1 to 5, inclusive, the abutment 65 is an open frame comprising transverse bars 66 in substantially the same plane with the longitudinal bars 21 of the upper side frame structure, and being of such length that their ends just clear said side frame

bars or rails 21. These abutment bars or rails 66 are secured on the front faces of the upright legs 67 of L-shaped bracket members whose horizontal legs 68 are extended forwardly and have secured on their under sides a series of transverse bars or slats 69 in spaced parallel relation and corresponding in dimensions to the transverse bars or slats 23 of the movable carrier or platform, hereinbefore described, said bars 69 constituting a slatted bottom for the article pusher element. Preferably, the bars or slats 66 and 69 are fastened to the angle bracket members 67 and 68 by means of rivets 70, of the same type as the hereinbefore described rivets 25, by which the transverse bars or slats 23 are fastened to the endless belts 24. In this connection it may be here stated that the foremost bottom bar or bars 69 of the article pusher element have the said endless belts 24 fastened to the under sides thereof so that, when the bars or slats 23 of the article carrier or supporting platform move forwardly or rearwardly, as the case may be, said article pusher element moves in the same direction therewith. In Figs. 6 and 7 the abutment member of the article pusher element 65 comprises a plate 66^a which is riveted or otherwise secured to the upstanding leg portions 67 of the bracket members, as in the structure of the article pusher element just previously described, and the bottom of the modified element comprising a plate 69^a in lieu of the hereinbefore mentioned bars or slats 69, said plate being secured to the forwardly extending horizontal legs 68 of the bracket members, and the endless belts 24 being secured to the under side of said bottom plate 69^a, as best shown in Fig. 7 of the drawings.

For convenience and facility in operating the movable article carrier or platform of the device, an endless belt 71 is preferably provided, substantially as shown. However, in some cases, the endless belt 71 may be omitted and the movable article carrier or platform moved forwardly and rearwardly by the operator grasping the transverse bars or slats 23 which are within reach, or, in other cases, other actuating means may be substituted for the endless operating belt 71, which latter is obviously very simple in its application and use and has been found to be very practical in most adaptations of the invention. As shown, the endless belt 71 is fastened to the under sides of the forward bottom bars 69, or to the under side of the bottom plate 69^a, as the case may be of the article pusher element 65, the belt 71 being passed over the rear roller 29 and also about the forward roller 28 with considerable slack so that a bight or open loop of considerable dimension is afforded at the front end of the shelf for the convenient grasping and manipulation of the belt in moving the movable article carrier or platform and the connected cooperating article pusher element at the rear thereof.

In order to permit the endless belts 24 which, of course, are maintained in tautened condition about the opposed rollers 28 and 29, and the transverse bars or slats 23 on said belts to make the turn around the forward roller 28, in the operation of the device, said operating belt 71 is carried up between the foremost bar 69, or the front edge of the plate 69^a, as the case may be, of said article pusher element 65, and the rearmost bar or slat 23 of said movable article carrier or platform, and thence carried forwardly over all of the bars or slats 23 which are riding on the longi-

tudinal angular guide members 22, said belt 71 also riding beneath the bars or slats 23 which happen to be below the belts 24 and riding on the flanges 16 of the side frame members 15.

5 In the use of the device, in loading it, the movable article carrier or platform is moved forwardly so as to bring the article pusher element 65 close to the front end of the body frame, this being accomplished by the operator pulling upon 10 the upper flight of the endless operating belt 71, and as the articles or commodities are placed on the device the movable carrier or platform is intermittently moved rearwardly by the operator pulling on the lower flight of the endless belt 71, and continuing the operation until the article 15 pusher element 65 reaches its rearmost position. Obviously, to unload the device the operation is reversed. It is, of course, understood that the front end of the body frame is open throughout 20 the entire width thereof except for the hereinbefore described channeled cross frame member 18, and possibly a supplemental cross frame member 18^a, as shown more clearly in Figs. 3 and 4 of the drawings. However, at the rear end of 25 the body frame, the upper side members are preferably connected by a cross bar 21^b which serves not only to brace the upper side frame members, but affords a limiting stop for arresting the rearward movement of the article pusher element 65.

30 In practice, the invention may be incorporated in a built-in structure in the form of a rack or shelf, or it may be obviously incorporated in a portable structure in the form of indoor or floor trucks, as well as regular outdoor service and delivery trucks. It is the last noted use for which 35 the invention is primarily intended, and for which the structure has been more particularly designed in order to take care of the various strains and torsions to which the bodies of the trucks and the contained racks or shelves are incidentally subjected in use.

In the adaptations of the invention the body frames on which the movable article carrier or supporting platform is mounted may be fixedly located, but in most cases the supporting frames will be removable, and to this end it is preferable to provide the body frame with rollers or other antifriction devices of some suitable type. As 45 shown in the drawings, the body frame is provided with disc-like rollers 72 which are located on the outside of the lower longitudinal frame members 15, said rollers 72 being journaled on shouldered studs 73, which are inserted through apertures provided therefor in the side frame 50 members 15 and secured in place by nuts 74. By this provision the racks or shelves may be readily placed upon and removed from supporting trackways provided therefor in the service or delivery truck or the like.

60 The device of the present invention facilitates the handling of articles and commodities of various kinds, particularly bakery goods and the general line of food products and other commercialized commodities, as the movable carrier or platform is readily loaded and unloaded from one end, thus obviating the necessity for the user reaching at great length in placing and removing articles or necessitating his entering the truck or moving from his position at the receiving and 65 delivering end of the device, which is one and the same.

As shown in the drawings, the device may be provided with a brush 75 extending transversely of the forward end portion of the body frame, 75 the brush being conveniently mounted within

the channeled end frame member 18, and the bristles projected inwardly of the device a distance sufficient to engage the bars or slats 23 as they pass around the front roller 28. This provision is of material advantage in keeping the movable platform bars or slats 23 in a clean and sanitary condition, and, obviously, the location of the brush element 75 may be changed as circumstances may dictate.

It may be here noted that the forward end portions of the upper flanges 16 of the body side frame members 15 are cut away sufficiently to permit the turning of the transverse bars or slats 23 with the endless belts 24 about the forward roller 28, that is to say, said upper flanges 16 terminate just short of the roller 28. It may be also noted that the upper side members of the body frame can be eliminated and the general structure and arrangement modified in many respects without in the least departing from the spirit and scope of the invention. For example, sprocket chains and gears may be substituted for the endless belts 24 and rollers 28 and 29 as shown, and various structural materials substituted or used in combination in the different parts of the device. The invention, therefore, is not limited to the precise construction and arrangement shown in the drawings, nor in the materials used.

Having thus described my invention, what I claim as new and desire to secure by Letters Patent is:

1. In a rolling shelf unit, a rectangular body frame, endless belt means on said body frame, a movable platform element comprising transverse slat members respectively secured to said endless belt means whereby to be movable the one by and with the other, means on said body frame for slidably supporting the opposite end portions of said platform slat members movably thereon separately from said endless belt means, and separate endless belt means connected to said platform element for moving said platform element and said first mentioned endless belt means in their connected relation.

2. In a rolling shelf unit, a rectangular body frame, endless belt means on said body frame, a foldable platform element secured to said endless belt means whereby to move longitudinally therewith, a separate pusher element located at the rear of and having a complementary platform portion cooperating with said foldable platform element, said pusher element being connected to said endless belt means whereby to be movable cooperatively with said means and platform element, means on said body frame for slidably supporting and guiding said movable platform element and said pusher element separately from said endless belt means in their movement with said endless belt means, and separate endless belt means connected to said platform and pusher elements for manually operating them simultaneously.

3. A portable rolling shelf of the character described, comprising a rectangular body frame, transverse antifriction roller supporting means on said body frame, normally tautened endless belt means on said antifriction roller supporting means operating longitudinally of said body frame, a foldable platform element movable longitudinally of said body frame and being connected to said endless belt means whereby to be moved the one by and with the other, means on said body frame for supporting said foldable platform element slidably thereon independently of

said endless belt means, and separate endless belt means, in normally loosened and extensible condition, for manually operating said first mentioned endless belt means and said connected 5 foldable platform element.

4. The herein described rolling shelf structure, comprising a rectangular body frame, a pair of transverse rollers supported in opposed relation to each other on said body frame, one of said 10 rollers being adjustably supported at its ends on longitudinal frame members, the other roller being mounted on longitudinally movable frame members having cooperating spring tension elements acting normally to move said last mentioned roller in the direction away from said adjustably supported roller, each of said rollers comprising a tubular outer member provided at its opposite end portions with internal antifriction bearings, a spindle rod extending axially 15 through said antifriction bearings, and coupling members for supporting said spindle rods on said longitudinal roller supporting frame members aforesaid, one end portion of each of said spindle rods being rigidly secured to its said coupling member, and the opposite end of the rod being 20 capable of longitudinal and rotative movement with relation to its coupling member.

5. The herein described rolling shelf structure, comprising a rectangular body frame, said frame 30 including channeled longitudinal side members with their flanges disposed inwardly, cross frame members connecting said side frame members, vertically flanged longitudinal guideways on top of said channeled side frame members, a foldable platform comprising transverse slat members 35 movably supported at their ends normally on said flanged guideways, said platform slat members in the movement and folding of said platform being movable to and slidably supported on the lower flanges of said channeled side frame members, a separate pusher element 40 having a horizontal article supporting base portion slidably supported on said longitudinal vertically flanged guideways cooperatively at the rear of said foldable platform, normally tautened endless belt means on said frame connected to the respective slat members of said platform and to said pusher element, whereby said slat members and said pusher element are operable the 45 one by and with the other and an additional endless belt, in normally loosened and extensible condition, for manually actuating said platform and said pusher element in either direction, forwardly or rearwardly.

55. 6. The herein described rolling shelf structure, comprising a rectangular body frame, said frame including channeled longitudinal side members with their flanges disposed inwardly, cross frame members connecting said side frame members, vertically flanged longitudinal guideways on top 60 of said channeled side frame members, a foldable platform comprising transverse slat members movably supported at their ends normally on said flanged guideways, said platform slat members in the movement and folding of said platform being movable to and slidably supported on the lower flanges of said channeled side frame members, a separate pusher element 65 having a horizontal article supporting base portion 70 slidably supported on said longitudinal ver-

tically flanged guideways cooperatively at the rear of said foldable platform, transverse opposed rollers in said body frame, one of said rollers being adjustable and resiliently held with respect to the opposite roller, endless belt elements 80 on said rollers, portions of said endless belt elements being secured to the under sides of said transverse platform slat members and said pusher element, and a supplemental endless belt element secured to the horizontal article supporting portion of said pusher element and extending in loosened condition forwardly therefrom and beyond the front end of the foldable platform.

7. The herein described rolling shelf structure, comprising a rectangular body frame, said frame including channeled longitudinal side members with their flanges disposed inwardly, cross frame members connecting said side frame members, vertically flanged longitudinal guideways on top of said channeled side frame members, a foldable platform comprising transverse slat members 90 movably supported at their ends normally on said flanged guideways, said platform slat members in the movement and folding of said platform 95 being movable to and slidably supported on the lower flanges of said channeled side frame members, a separate pusher element having a horizontal article supporting base portion slidably supported on said longitudinal vertically flanged 100 guideways cooperatively at the rear of said foldable platform, transverse opposed rollers in said body frame, endless belt elements on said rollers, portions of said endless belt elements being secured to the under sides of said transverse platform 105 slat members and said pusher element, and an operably connected supplemental endless belt secured to said pusher element, said last named endless belt from said pusher element being extended across the tops of said platform slat members 110 and around and under said rollers.

8. The herein described rolling shelf structure, comprising a rectangular body frame, said frame including channeled longitudinal side members with their flanges disposed inwardly, cross frame 120 members connecting said side frame members, vertically flanged longitudinal guideways on top of said channeled side frame members, a foldable platform comprising transverse slat members 125 movably supported at their ends on said flanged guideways, said platform slat members in the movement and folding of said platform being slidably supported on the lower flanges of said channeled side frame members, a pusher element 130 slidably supported on said longitudinal vertically flanged guideways at the rear of said foldable platform, transverse opposed rollers in said body frame, endless belt elements on said rollers, portions of said endless belt elements being secured to the under sides of said transverse platform 135 slat members and said pusher element, adjustable means acting upon said rollers for tautening said endless belt elements and exerting a yieldable tension in the tautening action, and an operably connected supplemental endless belt secured to said pusher element, said last mentioned endless belt from said pusher element being extended across the tops of said platform slat members 140 and around and under said rollers.

FLOYD J. POWELL. 145
